H. R. YARDLEY,
SOCKET COVER AND SHADE HOLDER.
APPLICATION FILED AUG. 12, 1915.

1,171,492

Patented Feb. 15, 1916.

UNITED STATES PATENT OFFICE.

HORACE R. YARDLEY, OF CHICAGO, ILLINOIS.

SOCKET-COVER AND SHADE-HOLDER.

1,171,492.

Specification of Letters Patent. Patented Feb. 15, 1916.

Application filed August 12, 1915. Serial No. 45,228.

To all whom it may concern:

Be it known that I, HORACE R. YARDLEY, a citizen of the United States, residing at Chicago, in the County of Cook and State 5 of Illinois, have invented a certain new and useful Improvement in Socket-Covers and Shade-Holders, of which the following is a full, clear, concise, and exact description, reference being had to the accompanying 10 drawings, forming a part of this specification.

My invention relates to socket cover and shade holder, especially to devices for holding shade or globes for lighting fixtures, 15 although the invention may obviously have other uses.

The principal object of the invention is to provide a simple, practical, inexpensive and effective device for detachably supporting a shade or globe for an electric or other 20 light.

A further object is to permit the ready and easy operation of the device so as to permit the shade or globe to be quickly attached or detached.

In the accompanying drawings Figure 1 is a view of a socket cover and shade holder embodying my invention with a globe or shade detachably supported thereby; Fig. 2 20 is a cross section taken on line 2--2 in Fig. 1; Fig. 3 is a view similar to Fig. 2 with the device in a different adjustment. Fig. 4 is a fragmentary view showing the device without the globe or shade.

35 In the drawings I show a socket cover and shade holder comprising a shell or casing 1 made more or less bell shaped, closed at the top and open at the bottom. A globe 2 is shown below and detachably supported by the shell or casing 1, the latter being provided with an enlarged flange or bottom portion 1^a which encircles the upper contracted portion of the globe or shade 2.

Within the mouth or flange 1^a is located 45 a spring clip 4, preferably in circular form, but with the ends 5--5 separated somewhat from one another and turned up at 5^a--5^a. The end portions 5 are preferably provided with inwardly projecting bent portions 50 6--6. The clip 4 is mounted loosely within the mouth 1^a and an adjusting member 7 is

secured to the clip 4, preferably about midway between its ends 5, said member 7 extending through a slot 8 in the mouth 1^a. The member 7 is provided with several 55 shoulders 9 which are located in the manner of a flight of steps, the several shoulders being at one side of and one above another. An abutment 10 adapted to engage the shoulders 9--9 is provided on the mouth piece 1^a 60 said abutment 10 being conveniently formed by one end of the slot 8. Each shoulder 9 is preferably provided at its outer edge with an upwardly extending projection 11 whereby by the abutment 10 may be held in engagement with the shoulders 9. A supplemental slot 12 is located at the side of abutment 10 opposite the slot 8, said slot 12 being adapted to receive a projection 11.

In using the device, the member 7 is adjusted in a more or less radial direction inwardly and outwardly to effect the engagement and disengagement of the globe or shade 2. For instance to engage said shade 2, the member 7 is pushed inwardly as far as 75 it can be conveniently and then moved to one side (to the left referring to Fig. 2) so as to cause the abutment 10 to be engaged by one of the shoulders 9 and its projection 11. In Fig. 2 the left hand shoulder 9 is held 80 firmly in the inward position into which it has been pushed and the clip 4 will be held in a contracted condition in which it will engage the neck of the globe 2, as shown in Fig. 2. Thus the globe will be detachably held in place. In order to release and detach said globe the member 7 is pushed first 85 inwardly a little, so as to disengage the projection 11 from the abutment 10 and then moved to one side (to the right) and then 90 allowed to be sprung outwardly by the clip 4, whereupon said clip 4 becomes disengaged, permitting the withdrawal and detachment of the neck of the globe 2. By having a series of shoulders 9 positioned as 95 shown, the desired degree of tightness and firmness to effectively hold the globe 2 may be secured, and at the same time provision is made for different sized necks for different sized globes or for globes of the same size having necks slightly varying, as is often the case in commercial manufacture.

- 2
- In Fig. 3 the member 7 is shown pushed well inwardly so that the farthest shoulder 9 is engaged by the abutment 10, thereby contracting the spring clip 4 to a considerable extent as required by the small size of the neck 2. In Fig. 4 the member 7 is shown in an outward position in which the globe neck will be disengaged and released so that it may be detached.
- 10 It will be understood that changes and modifications may be made without departing from the spirit of the invention.
- What I claim is:
1. A device of the class specified comprising a shell or casing, a spring clip arranged therein, a member for adjusting the size of said spring clip, said member being adapted to move inwardly and outwardly to vary the size of said spring clip, and passing through a slot in the shell or casing to permit actuation of said clip from outside of the shell or casing, and means whereby said clip may be locked in an inward position by a sidewise movement of said member.
  2. A device of the class specified comprising a shell or casing, a spring clip arranged therein, and a member for adjusting the size of said spring clip, said member being adapted to move inwardly and outwardly to vary the size of said spring clip and passing through a slot in the shell or casing to permit actuation of said clip from outside of the shell or casing, said member and shell or casing being provided with means for engaging one another so as to hold said member in an inward position, by a sidewise movement of said member.
  3. A device of the class specified comprising a shell or casing, a spring clip arranged therein, and a member for adjusting the size of said spring clip, said member being adapted to move inwardly and outwardly to vary the size of said spring clip and passing through a slot in the shell or casing to permit actuation of said clip from outside of the shell or casing, said member and shell or casing being provided with means for holding said member in an inward position, said means comprising a shoulder on said member and an abutment on said shell or casing to engage said shoulder, which shoulder and abutment may be engaged and disengaged by a sidewise movement of said member.
  4. A device of the class specified comprising a shell or casing, a spring clip arranged therein, and a member for adjusting the size of said spring clip, said member being adapted to move inwardly and outwardly to vary the size of said spring clip and passing through a slot in the shell or casing to permit actuation of said clip from outside of the shell or casing, said member and shell or casing being provided with means for
  - 5 holding said member in an inward position, 65 said means comprising a series of shoulders arranged in step-like manner on said member and an abutment on said shell or casing for engaging said shoulders.
  6. A device of the class specified comprising a shell or casing, a spring clip arranged therein, and a member for adjusting the size of said spring clip, said member being adapted to move inwardly and outwardly to vary the size of said spring clip and passing through a slot in the shell or casing to permit actuation of said clip from outside of the shell or casing, said member and shell or casing being provided with means for holding said member in an inward position, 70 75 said means comprising a series of shoulders arranged in step-like manner on said member and an abutment on said shell or casing for engaging said shoulders, said shoulders being provided with outwardly extending projections.
  7. A device of the class specified comprising a shell or casing, a spring clip arranged therein, and a member for adjusting the size of said spring clip, said member being adapted to move inwardly and outwardly to vary the size of said spring clip and passing through a slot in the shell or casing to permit actuation of said clip from outside of the shell or casing, said member and shell or casing being provided with means for holding said member in an inward position, 80 85 said means comprising a series of shoulders arranged in step-like manner on said member and an abutment on said shell or casing for engaging said shoulders, said shoulders being provided with outwardly extending projections.
  8. A device of the class specified comprising a metallic shell or casing open at one end and provided with a circumferential slot near said end, a spring clip comprising a spring wire extended circumferentially around the interior of the mouth portion of said shell or casing and having end portions opposite said slot in the latter, which end portions are provided with inwardly extending projections, an adjusting member 7 attached to said wire clip and extended

through said slot, said member being provided with a series of abutments arranged in step-like manner, said abutments being provided with locking projections 11, and 5 said shell or casing having a supplemental aperture adjacent said slot, said aperture being adapted to receive the projections on said shoulders and the portion of the shell or casing between said aperture and slot

forming an abutment to engage the shoulders 10 on said member 7.

In witness whereof, I hereunto subscribe my name this 23d day of July, A. D. 1915.

HORACE R. YARDLEY.

Witnesses:

CHAS. EUMMACH,
A. MILLER BELFIELD.

Correction in Letters Patent No. 1,171,492.

It is hereby certified that Letters Patent No. 1,171,492, granted February 15, 1916, upon the application of Horace R. Yardley, of Chicago, Illinois, for an improvement in "Socket-Covers and Shade-Holders," were erroneously issued to the inventor, said Yardley, whereas said Letters Patent should have been issued to *R. Williamson & Co., of Chicago, Illinois, a corporation of Illinois*, as assignee of the entire interest in said invention, as shown by the records of assignments in this office; and that the said Letters Patent should be read with this correction therein that the same may conform to the record of the case in the Patent Office.

Signed and sealed this 7th day of March, A. D., 1916.

[SEAL.]
